DESK TRAY

Werner C. Kipp, Morton Grove, Ill., assignor to Tarco Manufacturing Company, Evanston, Ill., a corporation of Illinois

Application June 29, 1959, Serial No. 56,575

Term of patent 14 years

(Cl. D74—1)

Fig. 1 is a front perspective view of a desk tray showing my new design;

Fig. 2 is an enlarged top plan view thereof;

Fig. 3 is a side elevational view looking in the direction 3—3 of Fig. 2; and

Fig. 4 is a front elevational view thereof looking in the direction 4—4 of Fig. 2.

The dotted line showing of the paper clip, writing instruments and perforated cover are for illustrative purposes only.

I claim:

The ornamental design for a desk tray, substantially as shown and described.
